UNITED STATES PATENT OFFICE.

CHRISTOPHER JOHN SULLIVAN, OF JUNEAU, TERRITORY OF ALASKA.

FISHERMAN'S KIT.

Application filed December 28, 1927. Serial No. 243,097.

The present invention relates to a fisherman's kit in which the various portions of his tackle used in angling may be compactly stored for accessible use. The invention 5 comprises a plurality of nesting receptacles hinged together and contains in compact and orderly arrangement, the various accessories necessary for his use.

In carrying out the invention I provide 10 preferably three sectional dished parts hinged together the hinges preferably being in different circumferential positions to permit more compact nesting. The several dished parts are preferably of circular formation, the two outer ones being more deeply dished or recessed and joined by a hinge 15 on one side and a spring latch on the other. The lower member is provided with a plurality of compartments with hinged covers to contain various small portions of the fisherman's tackle each compartment being 20 provided with a spring-pressed lid to retain the tackle with a compact central compartment containing retaining springs in which 25 may be supported hooks and gutted connections therefor in symmetrical order. The outer receptacle has a plain surface with a plurality of depressed receptacles to store anti-septics and a surrounding larger 30 annular concentric wall on which may be mounted the leaders. In the center of this pivoted member is mounted a rotary post for convenient use in reeling and unreeling the leaders. Pivotedly connected with this 35 outer member is a shallow folding pivoted metallic casing carrying a mirror for convenient use in field work.

The invention therefore essentially comprises a compact fisherman's kit or outfit for 40 storing his various forms of tackle composed of a plurality of foldable chambered receptacles with a plurality of spring lidded compartments for containing plain hooks, gutted hooks, reeled leaders, a field mirror, 45 anti-septic boxes and various other paraphernalia important to a fisherman's necessity or convenience.

The several features of novelty will be 50 more fully hereinafter described and will be specifically indicated in the appended claims.

In the accompanying drawings:

Figure 1 is a plan of a kit embodying my 55 improvements;

Fig. 2 is a plan of the kit opened; Fig. 3 is a median vertical section;

Fig. 4 is an enlarged plan of a lower section;

Fig. 5 represents a sectional detail of the 60 kit closed;

Fig. 6 is a part section of a hinged joint for the intermediate section;

Fig. 7 is a partial section of the hinged casing open;

Fig. 8 is a part section of the joint between the middle and outer section;

Fig. 9 is a detail of a latch.

Referring now particularly to the drawings, Figure 2 represents in open relation three hinged parts composing chambered receptacles capable of folding into close compact relation as indicated in Figure 3 the several compartments 1, 2, 3 are hinged together as at 4 and 5 on planes circumferentially displaced so that the section 3 may 75 fold into and rest within the receptacle 2 and the section 1 may be brought snugly against 2 with the edges in register and latch together by a spring latch hanging over a projection ledge 6^a. The sections 1 and 2 are 80 of the same depth whereas 3 is very much shorter and is provided with a flanged circular edge 18 to secure a mirror 19. The section 2 is provided with a series of depressions 20, 21 to accommodate receptacles 85 to contain medical supplies and 24 to permit of mounting a rotary winding stem for reeling off a line wound on radial pins 27 supported on cylindrical supports—connected with a depressed part of the casing 2. 90 The other outer member is divided into three transverse compartments the central one 14 containing a tension spring 11, 11^a at its respective ends to form a support for gutted or plain hooks having elastic coils 95 for convenient clamping.

In the side of the receptacle 1 adjacent the compartment 14 are formed a plurality of receptacles 15, 15^a, 15^b, 15^c, 15^d, 15^e, adapted to form receptacles in which to store 100 small fishing accessories such as loose fly hooks, spoons, miscellaneous articles, BB shot, single hooks, large sinkers, etc., each of which is provided with a normally spring-closed lid, the central storage compartments 105 where springs 14 in their spirals clamp gutted, plain and fly hooks are also provided with a spring-controlled lid, the several lids being provided with means for raising them as a recess to receive the finger nail. The hinge 4, carrying the field mirror, is displaced circumferentially with reference to 110

the hinge 5, the sheet metal backing of which is of smaller radius than the members 1 and 2 so that when the kit is compacted it will lie snugly related to the outer compartments of the container 1 and 2.

It will be thus apparent that I have provided a kit for storing fishing paraphernalia well adapted for convenient service of the fisherman and carrying in a very small compact 10 conveniences adapted to his several needs. Access to the antiseptics may be obtained by moving the pivot lid 22 without opening the kit, and when the kit is opened any desired accessory may be conveniently 15 removed. By raising the handle 26 a leader may be unreeled by leading it from the supports 27 and rotating the carrier on which they are mounted.

Having thus described my invention, 20 what I claim as new and desire to secure by Letters Patent, is:—

1. A fisherman's kit comprising a pair of hinged circular disk shaped members having a spring latch connection, one member having partitioned compartments to hold hooks and further fishing paraphernalia, each compartment being provided with a spring lid, 25

the other member having on its outside a circular depression of less diameter containing outside pockets and lids therefor for medical supplies, and a rotary unreeling member, guide pins on the inner periphery of said depression adapted to contain coiled lines, and a hinged cover for said member, said hinge being offset from the first mentioned hinge connection. 30 35

2. A fisherman's kit comprising a pair of cupped receptacles, a hinge connecting them, latching means for retaining them closed, the one receptacle containing in the inside independent normally closed compartments for various forms of small tackle, each having a spring lid, the other outside receptacle having a depressed central part with a plurality of receptacles for easy accessible medical supplies on its outside, a circular wall on its inside with detents for storing lines, and a hinged cover adapted to nest within the last mentioned receptacle having its hinge offset with respect to the aforesaid hinge connection. 40 45 50

In testimony whereof I affix my signature.

CHRISTOPHER JOHN SULLIVAN.
